UNITED STATES PATENT OFFICE.

JOHN C. PAGE, OF OAKLAND, CALIFORNIA, ASSIGNOR TO STANDARD BRASS CASTING CO., OF OAKLAND, CALIFORNIA, A CORPORATION OF CALIFORNIA.

SHOWER HEAD.

Application filed January 16, 1924. Serial No. 686,555.

To all whom it may concern:

Be it known that I, JOHN C. PAGE, a citizen of the United States, residing at Oakland, county of Alameda, and State of California, have invented new and useful Improvements in Shower Heads, of which the following is a specification.

This invention relates to bath-room fittings and particularly pertains to shower heads.

Prior to my invention, shower heads were fitted with removable perforated face plates for the purpose of permitting access to be had to the interior of the head for cleansing purposes. These heads and plates were of metallic construction permitting the face plate to be threaded or screwed onto the head. Due to this metallic construction the shower heads were difficult to keep clean and polished, and soon became tarnished under the extreme conditions to which fittings of this character are exposed. On account of the necessity of having a threaded or like connection between the face plate and head, it was impractical to construct the parts of porcelain or like non-corrodible material.

Therefore, it is the principal object of the present invention to generally improve devices of the character referred to whereby to provide a generally improved shower head which may be formed of porcelain or like non-corrodible material, the face plate of which shower head is removable to facilitate cleansing of the interior of the fitting. The device is of simple and inexpensive construction, easily cleaned, and neat in appearance.

In carrying out this object I provide a porcelain shower head, the upper end of which is clamped to a fitting which may be connected with a shower bracket. The face plate of the shower head is separate from the head proper and is clamped on the end of the latter by means of a stud which is secured at one end to the fitting mentioned and projects downwardly through the face plate to receive a clamping nut located exteriorly of the face plate.

One form which the invention may assume is exemplified in the following description and illustrated by way of example in the accompanying drawings in which:

Fig. 1 is a vertical section through a

shower head embodying the present invention.

Fig. 2 is a transverse section taken on line 2—2 of Fig. 1.

Referring more particularly to the accompanying drawings, 10 indicates a sleeve fitting having an exteriorly threaded end 11 by which it may be connected to a shower bracket. The lower end of this fitting is interiorly threaded for the reception of the threaded end of a clamping nipple 12. The lower end of this nipple is formed with an annular flange 14 which is adapted to engage the underside of an annular shoulder 15 formed interiorly of the upper end of a bell-shaped head member 16. A gasket 17 is interposed between the upper side of the annular shoulder 15 on the head member and a flange 18 formed on the lower end of the sleeve. The nipple 12 is screwed into the sleeve fitting 10 to compress the gasket 17 between the upper end of the head member 16 and the flange 18 on the fitting 10.

The lower or flared end of the head member 16 is formed with a downwardly projecting annular rim 19. Fitting over this end of the head member is a perforated face plate 20, the upper surface of which is formed with an annular channel or groove 21 which is formed adjacent the marginal edge of the face plate to receive the rim 19 of the head member. A gasket 22 is placed between the rim 19 and the surface of the groove 21 to render the joint water-tight.

To hold the face plate in proper position on the head member, I provide a stud 23, the upper end of which is threaded in the boss 24 of a spider formed over the mouth of the lower end of the clamping nipple 12. The lower end of the stud projects through an opening in the face plate to receive a clamping nut 25. By removing this nut the face plate may be removed and access may be had to the interior of the head member for cleansing or other purposes. The boss 24 is shown as hexagonal so as to receive a wrench.

It is preferred that the head member and the face plate be formed of porcelain or other non-corrodible material easily kept clean and polished.

To assemble the fitting, the head member and gasket are arranged on the clamping nipple and the latter is screwed into the

sleeve fitting 10 by applying a wrench to the boss 24 so as to tightly compress the gasket between the fitting 10 and the top of the head member. The stud 23 may 5 then be threaded into the boss 24 of the spider on the clamping nipple. The face plate is then placed over the end of the stud with its channeled edge, which is fitted with a gasket, engaging the rim on the end of 10 the head member. The clamping nut 25 is then threaded on the stud to clamp the face plate in position. Tightening the stud or bolt 23 will serve not only to compress the gasket 22 but also the gasket 17 by 15 reason of the fact that the member 16 will be thrust upwardly by the pressure applied to the plate 20.

It is obvious that to remove the face plate it is only necessary to remove the clamping 20 nut 25.

By my invention, I have provided a neat appearing shower head of inexpensive construction and which may be formed of porcelain or like non-corrodible material so that 25 it may be easily kept clean.

While I have shown the preferred form of my invention as now known to me, I wish it understood that various changes may be made in its construction without departing from the spirit of the invention as 30 defined in the appended claims.

Having thus described my invention, what I claim and desire to secure by Letters Patent is:—

35 1. In a shower head the combination with a pipe fitting formed with a flange, a clamping nut adapted to be threaded on to said fitting, a porcelain member forming the bell or funnel of a shower head clamped in place 40 between said nut and flange, a spider on said clamping nut formed with a wrench engaging boss, a perforated disk removably fitted to the base of the porcelain member, a bolt extending through the disk and con-

nected to the boss for clamping the disk in 45 position, said boss also serving when the disk is removed as a means to receive a wrench for turning the clamping nut, whereby when the nut is removed from the pipe fitting the porcelain member may be instantly separated from the parts which connected it in place.

2. In a shower head the combination with a metal pipe fitting, of a metal nipple threaded on to the pipe fitting, a porcelain 55 member clamped between the nipple and pipe fitting and constituting the funnel or bell of the shower head, a perforated plate or disk also of porcelain removably fitted to the flared end of the bell or funnel-shaped member, a spider formed on the lower end of the clamping nipple, a boss on the spider, and a bolt connected to the 60 boss and extending through the porcelain disk for clamping the latter to the base of 65 the bell or funnel-shaped member.

3. In a shower head the combination with a metal pipe fitting, of a metal nipple threaded on to the pipe fitting, a porcelain member between the nipple and pipe fitting 70 and constituting the funnel or bell of the shower head, a perforated plate or disk also of porcelain removably fitted to the flared end of the bell or funnel-shaped member, a spider formed on the lower end of the nipple, a bolt connected to the spider and extending through the porcelain disk for clamping the latter to the base of the bell or funnel-shaped member, a compressible 75 gasket between the top of the bell or funnel shaped member and the pipe fitting, and a compressible gasket between the base of the bell or funnel-shaped member and the perforated disk whereby when the bolt is tightened both of said gaskets are compressed to 80 form watertight joints.

JOHN C. PAGE.
